UNITED STATES PATENT OFFICE

LARKIN R. SHAFFER, OF GARLAND, UTAH

SWITCH-STAND LOCK

Application filed October 5, 1926. Serial No. 139,677.

This invention relates to improvements in switch stand locks and particularly to a lock for a stand of what is known as a ground throw switch, this type of stand being a comparatively low structure adapted for use in yards where high switch stands can not be used. The switch stand of the present type is illustrated in my prior Patent No. 1,565,679, dated December 15, 1925.

Generally stated, the primary object of the present invention is to provide a switch stand which will not suffer damage in the event that the switch lever is in locked position while the switch points are not properly lined

up. More specifically, in stands of the present type, the switch lever is held down by a pivoted arm or latch, and when a train or one or more cars runs through a switch whose points are not properly lined up, it frequently

happens that the arm which is supposed to hold the switch lever down will take all of the strain caused by the movement of the improperly positioned switch point, and as a result either the switch stand will be twisted, the

latch arm will be sprung, or other portions of the mechanism will be so affected that the switch points will remain open to such an extent when the lever is in its normal switch closing position that a train subsequently

heading in on the switch will be derailed. To overcome this likelihood of injuring the switch stand or other parts, and rendering a train liable to derailment, the present invention provides means for permitting the switch

lever to move independently of its latch arm in the event a train passes over a switch whose points are not properly lined up. In the preferred embodiment of the invention, this result is accomplished by having the lever latching arm, which is pivoted in the switch stand

casing, formed with a somewhat weakened free end portion adapted to engage the switch lever, whereby when there is a tendency of the improperly aligned switch points to move the switch lever, the latter will break off the weakened end portion of its latching arm, and be free to move to any extent necessary to compensate for movement of the improperly aligned switch points.

A further object of the invention is to pro-

vide a switch stand casing which may be permanently attached to a solid base while still permitting the lever latching arm to be inserted therein or removed therefrom in the event the lever latching arms become broken as before outlined, and it is necessary to install a new lever latching arm.

With these and other objects in view, the invention consists in certain novel details of construction, and combinations and arrangements of parts, all as will hereinafter be more fully described and the novel features thereof particularly pointed out in the appended claims.

In the accompanying drawings: 65
Figure 1 is a vertical sectional view taken through the switch stand casing, and

Figure 2 is a sectional view taken on the line 2-2 of Figure 1.

Practically the entire switch stand is constructed substantially the same as in my prior patent above referred to, and a detailed description is not believed to be necessary. Suffice it to say the switch lever 10 is received in a vertically disposed slot 11 in the casing 12, so that it rests quite close to the ground when in its normal locked position. A latch 13 is adapted to overlie the switch lever, and lock it in the position shown, under which circumstances the switch points of the switch controlled by the lever are supposed to be properly lined up. Preferably, latch 13 consists of a wheel journaled with pin 14 in the casing, this wheel having a plurality of arms, one of which overlies the switch lever. A second arm of said wheel is held by an abutment 15, so as to prevent the latch wheel rotating and releasing the lever 10. Abutment 15 is preferably a cross bar carried near the inner extremity of an operating handle 16 whose other extremity is outside casing 10, where the operator's foot can be placed upon it to depress the same and lift abutment 15 out of the path of the latch arm which it normally engages. In Figure 1, the parts are shown in locked position in full lines, and in unlocked position in dotted lines. When unlocked, wheel 13 is free to rotate on its pivot and will do so as lever 10 is raised to throw the switch. This movement of the lever 10 100

and the latch 13 will bring the lowermost arm indicated at 17 into position across slot 11, so that as the switch lever is restored to its normal lower position, the wheel 13 will be moved 5 reversely and restored to its original position. While the cross bar or abutment 15 could be relied upon to hold the latch 13 against rotation, it is preferred that a ring 18 be carried on said abutment and positioned to engage the 10 latch wheel. This arrangement will appreciably reduce the shocks that would otherwise be placed on the structure.

As before mentioned, if the parts were in their normal locked position as shown in full lines in Figure 1, and the points of the switch controlled by the lever 10 were not properly lined up, upon passage of a train over the switch, there will be a tendency of the lever 10 to rise in the slot 11, and this movement of the lever naturally will result in a strain being placed on some portion of the device. The present invention, however, eliminates any damage being done under such circumstances by having the several arms of the latch wheel 13 formed near their free outer ends with lines of weakness 19 of such formation that while the extremities of the latch arms are of sufficient strength to maintain the lever locked when under normal conditions, nevertheless, if the lever 10 should be caused to be moved upwardly by reason of the switch points not being properly lined up, the weakened end portions of the arm engaging lever 10 will be broken off, thereby permitting the 30 lever 10 to rise as far as necessary. By thus permitting the lever 10 to rise in the slot, the switch points will be left open and the engine or cars of the train can pass through without doing any other damage. After the extremity of one latch arm has been broken, the wheel can be given a one-fourth revolution so that a new point is positioned to engage the switch lever. From the foregoing it will be readily seen that under normal conditions the switch 40 lever can be locked against movement, but under abnormal conditions, such as the points of the switch not being properly lined up, the switch lever is capable of moving independently of its latching arm moving about its pivotal center, and independently of any movement of the abutment which holds the latch arm in engagement with the switch lever. As before noted, when a switch has been split, the arm of the latch wheel which holds the lever 50 10 down will break off and will allow said lever to go free and not stand cocked and said lever will also drop back in place, thereby reducing the number of derailments. Of course, it is not necessary that each of the arms of the latch wheel be formed with weakened end portions. Only two of them need be so formed, but in such a case care will have to be taken in mounting it in the casing.

In view of the fact that the present invention contemplates renewing the latch wheels

13 each time two of its arms have been broken, means are also provided in the present instance for facilitating the removal of a broken wheel and the insertion of a new one without the necessity of disturbing the switch stand or removing any of the securing elements by which the casing is mounted in place. Such means for facilitating this renewal of the latch wheel consists in having the sides of the casing 12 formed with rather enlarged openings 20 through which either a new or broken latch wheel may be passed. These openings in the casing are located beneath normal position of the latch wheel so that by removing the cross pin 14 on which said wheel is journaled, so said wheel is free to fall to the bottom of the casing where it may be then removed. A new wheel can then be inserted through the opening 20 and with very little manipulation positioned upwardly within the casing so that the cross pin 14 may again be restored. As shown in Figure 2, the cross pin 14 is held in place in the casing by an ordinary cotter pin. By thus providing for the renewal of the breakable latch wheels, considerable time, 90 labor and material is saved.

I claim:—

1. In a switch stand lock, the combination of a casing, a switch lever, a pivoted latching arm having a weakened free end portion 95 adapted to engage said switch lever, and means for releasably locking said latching arm in engagement with said lever.

2. In a switch stand lock, the combination of a casing, a switch lever, a latch comprising 100 a plurality of integral arms journaled within the casing, one of said arms being adapted to engage the lever, and means engaging another of said arms to hold the latch in lever locking position within the casing, said casing having 105 an unobstructed opening through which the integral latch arms may be inserted or removed.

3. In a switch stand lock, the combination of a casing, a switch lever, a latch comprising 110 a plurality of integral arms journaled within the casing, one of said arms being adapted to engage the lever, and means engaging another of said arms to hold the latch in lever locking position within the casing, said casing having 115 an unobstructed opening in the side thereof below the point at which said latch arms are journaled, said integral latch arms being insertable in and removable from the casing through said opening.
